United States Patent Office

Des. 186,924
Patented Dec. 22, 1959

186,924

PENCIL

John J. Lakatosh, East McKeesport, Pa.

Application May 8, 1959, Serial No. 55,828

Term of patent 7 years

(Cl. D74—24)

The essential features of my design reside in the portions shown in solid lines on the drawing.

I claim:

The ornamental design for a pencil, as shown and described.
